HEAD AND BACK REST FOR CHAIRS AND BEACHES, WITH FLAPS

Charles Fleisig, New York, N. Y.

Application July 12, 1951, Serial No. 15,845

Term of patent 14 years

(Cl. D15—8)

To all whom it may concern:

Be it known that I, Charles Fleisig, a citizen of the United States, residing at New York, in the county of New York and State of New York, have invented a new, original, and ornamental Design for a Head and Back Rest for Chairs and Beaches, with Flaps, of which the following is a specification, reference being had to the accompanying drawings, forming a part thereof.

In the drawings:

Fig. 1 is a front view of a head and back rest for chairs and beaches, with flaps, in open position, showing my new design;

Fig. 2 is a side view of the same in open position;

Fig. 3 is a rear view of the same in open position;

Fig. 4 is a front view thereof in closed position;

Fig. 5 is a rear view thereof in closed position;

Fig. 6 is a bottom view of it in closed position.

I claim:

The ornamental design for a head and back rest for chairs and beaches, with flaps, as shown.

CHARLES FLEISIG.
